AUTOMATIC RECORD FILE

Filed Dec. 2, 1925

2 Sheets-Sheet 2

UNITED STATES PATENT OFFICE.

GLEN D. COOPER, OF LEON, IOWA, ASSIGNOR OF ONE-HALF TO CHARLES H. JOHNSTON,
OF LEON, IOWA.

AUTOMATIC RECORD FILE.

Application filed December 2, 1925. Serial No. 72,833.

The object of my invention is to provide an automatic record file of simple, durable and inexpensive construction.

More particularly, it is my object to provide an automatic record file having compartments or separators which can be automatically moved from one end to the other of a series.

It is a further object to provide in such a device an inclined casing with a series of compartment members or separators adapted to slide toward the lower end of the casing and to provide means whereby one member at the lower end may be shifted automatically from the lower end to the upper end of the series.

It is another purpose to provide in such a device means for preventing the operation of the automatic mechanism whenever the lower compartment contains cards or the like, so that the lower compartment must be emptied before the device is operated.

With these and other objects in view, my invention consists in the construction, arrangement and combination of the various parts of my automatic record file, whereby the objects contemplated are attained, as hereinafter more fully set forth, pointed out in my claims, and illustrated in the accompanying drawings, in which:

Figure 1 is a front elevation of an automatic record file embodying my invention.

Figure 2 is a side elevation of the same, parts being shown in section and parts being broken away.

Figure 3 is a detail, transverse, sectional view taken on the line 3—3 of Figure 2.

Figure 4 is a detail, sectional view of part of the operating mechanism.

Figure 5 is a detail, sectional view taken on the line 5—5 of Figure 2.

Figure 6 is a detail, sectional view taken on the line 6—6 of Figure 2.

Figures 7 and 8 are longitudinal, sectional views of the lower end of the casing, showing the controlling parts in different positions; and

Figure 9 is an enlarged, detail, sectional view illustrating the engaging finger on the operating chains.

My improved device comprises a container indicated generally by the reference char-

acter 10, which may be of any suitable material, size and shape for the purpose.

The container is higher at the rear than at the forward end and is of proper width for the records to be kept.

The container 10 has the bottom 10^a, the front wall 10^b, the higher, rear wall 10^c and the side walls 10^d.

The container has in its upper portion a bottom member 11 inclined from its upper end to its lower end and terminating short of the lower end, as shown for instance in Figures 7 and 8.

This bottom member together with the upper portions of the sides 10^d of the container forms a record receiving case.

It is my purpose to provide in this case thus formed a series of separators, preferably having the form of compartment members, whereby compartments may be formed to receive records, such as cards or the like.

These compartment members are indicated generally by the reference character 12 and in each instance comprise a front wall 12^a and side walls 12^b. The lower edges of the side walls are beveled as at 13 to correspond to the inclination of the bottom member 11, so that normally the front walls 12^a will stand upright.

The compartment members 12 are arranged in a series as shown for instance in Figure 2 with the inner edges of the walls 12^b engaging the front surfaces of the walls 12^a, in succession as clearly shown in the drawings.

The upper edges of the side walls 12^b are likewise beveled as shown at 14.

The front walls 12^a have in their upper edges preferably at the middle, notches 15, as shown in Figure 1, to permit convenient access to the cards or other contents of the compartments.

For purposes of illustration, I may suggest that this device may be used for keeping records for a period of one month, and I therefore preferably use thirty-one of the compartment members 12 to correspond to the thirty-one days of the longest month, and these compartment members are preferably provided with indicating numerals 16, as shown in Figure 1. Extra cards are placed in the various compartments for keeping the

memorandum of matters to be attended to on various days of the next succeeding month.

It will be seen that it is desirable to have the compartment containing the cards for the current day at the lower front portion of the casing above referred to.

In order to accomplish this purpose, I provide means for automatically taking out 10 the lower compartment member 12 and carrying it to the upper part of the series.

It is also desirable that the mechanism for so transferring the compartment member should be inoperative until some disposition 15 has been made of the cards in the lower compartment, and so I have provided means whereby the contents of the lower compartment prevent the operation of the transfer mechanism.

20 The transfer mechanism will now be described.

Transfer mechanism.

It will have been noted that the bottom 11 25 terminates short of the lower end of the casing which contains the compartment members 12. I provide below the lower end of the bottom 11 for closing the opening between the lower edge thereof and the front 30 wall 10^b of the main container, a slidable bottom member 17 arranged to slide in guides 18 supported by the side walls 10^a of the main container just underneath the bottom 11. Means hereinafter described are provided for sliding this bottom member 17 for releasing the lowermost compartment member 12. That means will now be described.

In the central lower part of the bottom 40 member 17 is an elongated notch 19 shown for instance in Figure 3.

Mounted in the notch is a trigger plate 20 having downwardly projecting ears 21 which register with similar, downwardly 45 projecting ears 22 formed on the false bottom 17 adjacent to the opening 19 therein.

The ears 21 are pivoted to the ears 22 by means of a pintle 23 shown in Figures 3, 7 and 8.

50 The trigger plate 20 is almost balanced, but has a little more weight above its pivot than below it so that the upper end will tend to swing down.

However, when there is a card in the lower 55 compartment resting against the lower end of the trigger plate 20, it will depress the lower end and thus raise the upper end of such trigger plate.

60 Fixed to the bottom of the trigger plate is a spring plate 24 which projects downwardly along the trigger plate 20 and is so arranged that its resiliency tends to hold the lower part downwardly away from the trigger plate 20, as shown in Figure 7.

At the lower end of the spring plate 24 is 65 the upwardly projecting hook member 25.

The front container wall 10^b has a transverse groove 26 to receive the lower edge of the false bottom 17 as shown in Figure 7 and to partially receive the hook 25. 70

The upper edge of the trigger plate 20 has a downwardly inclined finger 27 shown in Figure 2.

Springs 28 secured to the upper portion of the sliding false bottom 17 and to the 75 guides 18, as shown for instance in Figure 3, normally tend to hold the false bottom 17 at the lower limit of its movement.

Below the opening at the lower end of the bottom 11 is a cross bar 29 in which is an 80 adjustable screw 30 extending just below the spring 24, as shown in Figures 7 and 8, and so located that when the movable bottom 17 is at the lower limit of its movement, the screw 30 does not affect the position of 85 the spring, but when the movable bottom is pulled upwardly, the spring 24 slides over the screw 30 for causing the hooked member 25 to be forced upwardly as shown in Figure 8. 90

The springs 28 normally hold the slidable bottom member 17 at the lower limit of its movement.

For pulling the bottom upwardly and thus letting the lowermost compartment member 95 12 drop out of the casing and for then carrying such lower member to the top of the casing and replacing it in the series, the following means have been provided:

Slidably mounted in guides 31 is a rod 32 100 having on its lower end a hook 33 for co-acting with the hook member 27.

When the rod 32 is pulled upwardly, it will engage the hook 27 for sliding upwardly the trigger plate 20 and the slidable 105 bottom 17. This is true, of course, when the upper end of the trigger plate 20 is allowed to drop downwardly to position where the hook member 27 will be in the path of the hook 33. 110

If there is a card in the lowermost compartment, it will weight down the lower end of the trigger plate 20 and keep the upper end thereof raised, so that when the rod 32 is pulled upwardly, the hook 33 will clear 115 the hook 27 and there will be no actuation of the trigger plate 20 or the bottom 17.

In the upper part of the container 10 is mounted a shaft 34. On the shaft 34 is a mutilated gear 35 from which part of the 120 teeth are omitted for a short distance as at 36. A gear casing 37 is provided for the gear 35 and the other pinions hereinafter referred to.

Pivoted to the casing 37 adjacent to the 125 gear 35 is a bell crank lever 38 shown in Figure 4. On the gear 35 is a projecting pin 39 so arranged that in the rotation of the

gear 35, the pin 39 engages one arm of the bell crank lever for rocking the lever a certain distance before the pin 39 clears such arm.

5 A rod 40 projects from the end of the other arm of the bell crank lever 38 through a curved slot 41 in the wall 10^a and is pivoted to a link 42 and extends through an eye 40^a in the upper end of the rod 42, which in turn is pivoted to the rod 32.

The rod 40 extends across the container 10 and has its farther end received in a socket 40^b in such manner as to form practically a pivotal connection.

15 The lever 38 is provided with a supplementary casing 43 forming part of the casing 37.

The pivot pin 44 of the lever 38 is really supported by the casing portion 43.

20 It will be seen that when the gear 35 is rotated, the pin 39 will engage the arm 38^a of the bell crank lever 38 for rocking the lever and moving the link 42 to the right from its position shown in Figure 2 for sliding the bottom member 17 to its open position.

On the shaft 34 outside the casing 37 is a crank arm 45.

In the upper part of the container 10 is a transverse shaft 46 on which is a pinion 47 meshing with an intermediate pinion 48 on the shaft 49. The pinion 48 is intended to link with the teeth of the gear 35.

On the shaft 46 are sprockets 50 in line with the sprockets 51 at the lower forward part of the container 10. The sprockets 51 are mounted on a transverse shaft 52.

On the pairs of sprockets 50 and 51 are chains 53. On the chains 53 are equi-distantly spaced curved fingers 54 arranged in opposite pairs. The upper stretches of the chains 53 travel close to the upper edge of the bottom 11.

Secured to the inside surface of the front wall 10^b is a spring 56 shown in Figure 2, the purpose of which will be later referred to and just at the lower end of that spring is a shelf or the like 57.

At the upper end of the casing having the bottom member 11 is a casing wall 58 inside the container 10, which is curved from top to bottom as shown in Figure 2 and has the slots 55 at its lower edge for the chains 53 and the fingers 54.

Secured to the wall 58 near its lower part is a spring 59 which is curved upwardly and forwardly as shown.

In the side of the gear 35 is a depression 60.

60 In the casing 37 is provided a socket 61 in which is received a spring 62 and a short plunger 63 having a rounded, outer end adapted to coact with the depression 60.

I will now describe the practical operation of my improved automatic record file and I

believe that during such description, the construction will be made clearer.

Thereafter, I shall describe the magazine which I preferably provide in the container 10.

Let it be assumed that the compartment members 12 are all arranged in series as shown for instance in Figures 1 and 2.

The memorandum cards for the various days of the month are placed in the various compartments.

Ordinarily, it is to be expected that the memorandum cards in the lower compartment will be taken out and the business referred to thereon in some way taken care of.

All of the cards must be taken out before the device can be operated, because if any card is left in the lower compartment, it will hold the forward end of the trigger plate down, and thus hold the curved hook member 27 out of the path of the hook member 33.

When the last card has been taken out of the lower compartment, the operator grasps the crank handle 45 and gives to it one complete revolution. He can readily determine when the revolution has been completed, because the plunger 63 will enter the depression 60 and indicate the completion of the operation.

At the beginning of a revolution and of a cycle of operations of the device, the hook members 54 are at the extreme lower end and the extreme upper end of the chains 53.

The first part of the rotation of the gear 35 does not affect the pinions 48 and 47 because of the fact that there are no teeth on the portion 36 of the gear 35.

The first part of this rotation of the gear 35 does, however, bring the pin 39 to position for rocking the lever 38 for moving the link 42 and the rod 32 to the right. This movement causes the hook member 33 to engage the hook 27 on the trigger plate 20 for carrying the trigger plate and the bottom member 17 upwardly.

The bottom member 17 slides in the guides 18.

When the bottom member 17 slides out from under the lowermost compartment member 12, that compartment member drops downwardly as indicated by the arrow in Figure 8.

In order to prevent the cards in the next upper compartment from dropping, it will be noted that the hook member 25 on the spring 24 is slid upwardly as it clears the front wall 12^a of the lowermost compartment member 12 on account of the engagement of the spring 24 with the screw 30.

This causes the hook member 25 to engage the wall 12^a of the next compartment member 12, as shown in Figure 8, and slides the series of compartment members upwardly slightly and far enough so that the

bottom member 17 will close the lower end of the compartment member 12 so engaged by the hook 25.

The lowermost compartment member 12 drops downwardly as shown by the dotted lines in Figure 2, engages the spring 56, which is so shaped as to cause the said compartment member to drop to flat position lying on the chains 53. When the gear 35 is rotated a little farther, the pin 39 (see Figure 4) clears the arm 38^a of the bell crank lever 38, whereupon the springs 28 shown in Figures 2 and 3 will slide the bottom member 17 downwardly again.

15 The continued rotation of the gear 35 causes the teeth thereon to engage the teeth of the pinion 48 for rotating that pinion and consequently the pinion 47 and the shaft 46 and the sprockets 50 for advancing the 20 chains 53 and bringing the lower fingers 54 into engagement with the lower edge of the compartment member 12 lying on the chains.

25 The chains are so spaced that the side walls of the compartment member 12 are farther apart than the chains, so that the main wall 12^a of the compartment member rests directly on the chains.

30 The fingers 54 engage the lower edge of the wall 12^a and carry the compartment member upwardly until it reaches the wall 58, which is of such width as to permit the side walls 12^b of the compartment member to lie at the opposite edges of the wall 58 overlapping such edges.

35 The compartment member 12, being carried up the chains, passes upwardly between the bottom 11 and the wall 58 and presses against the spring 59, forcing it toward the wall 58.

40 The curved fingers 54 as they start around the sprockets 50 lift the compartment member 12 away from the sprockets 50 and upwardly, whereupon as soon as the lower edge 45 of the compartment member 12 clears the upper edge of the bottom 11, the spring 59 will kick the compartment member 12 upwardly and forwardly until the lower edge thereof rests on the bottom 11.

45 It will, of course, be understood that the series shown in Figure 2 will have slid downwardly one compartment thickness, after the lowermost compartment member 12 has been dropped out of the series.

50 This cycle of operations may be repeated whenever it is desired to carry the lowermost compartment member to the upper end of the series.

55 The advantages of my device will be largely understood from the foregoing description.

60 I have provided a convenient office accessory arranged for the convenient use of blank printed forms or colored cards, which 65 may be filed and sorted for reference or re-

minder for any succeeding day for a period of one month.

A compartment is provided for each day. The date of each compartment is visible at all times and it is easy to observe the arrangement of all the dates on account of the slanting arrangement of the casing at the top of the container 10.

65 Incidentally, I preferably provide a window 64 in the wall 10^b, through which may be seen date indicia 65 on the front of the respective compartment members 12. Each day memorandum cards for the day will be in the lowermost compartment readily accessible for such use as may be desirable.

70 Until all the cards of the lowermost compartment are removed, it is impossible upon ordinary operation of the machine to transfer the lowermost compartment member 12 from the lower end of the series to the upper 75 end of the series. When, however, all of the cards are removed from the lowermost compartment, the operator simply turns the crank handle 45 and operates the mechanism of the machine for mechanically transferring the lowermost compartment member 12 from the lower part of the series to the upper 80 part of the series.

85 The whole series during this operation moves downwardly the distance of one compartment thickness.

90 It will be noted that when the bottom member 17 is slid out from under the lowermost compartment member and the remaining compartment members of the series are 95 slid upwardly a short distance, the weight of the stack will tend to engage the beveled edge 14 of the upper side wall of the lowermost container for contributing to forcing the lowermost container downwardly.

100 I provide in the lower part of the container 10 a magazine 66 for cards 67. At each side of the container 10 is an elongated slot 68 and the material at the lower edge of the slot is out-turned as at 69. (See Figure 6.)

105 Projecting into the magazine 66 is a V-shaped separator 70.

110 At the middle of the bottom of the magazine is a block 71 to which are secured springs 72 curved upwardly and outwardly as shown in Figure 6 and having at their upper ends curved finger portions 73 adjacent to the lower edges of the slots 68.

115 Cards 67 are placed in the magazine at each side thereof, and their upper edges are pressed towards the slots 68 by the springs 72 for making it easy to slip the cards out of the magazine. The cards are inserted into the magazine through a door 74 at the back 120 of the container 10.

125 Changes may be made in the details of the construction and arrangement of the parts of my improved record file, and it is my intention to cover by my claims, any 130

modified forms of structure or use of mechanical equivalents, which may be reasonably included within their scope.

I claim as my invention:

1. In a record keeping device, a case, a series of compartment members therein, mechanism for moving the members successively from one end to the other of the series in the case and for successively permitting the series to advance substantially the width of one member, and means for preventing the operation of the device until the contents have been removed from the compartment member next in order to be so moved.
2. In a record keeping device, a case, a series of compartment members therein, a movable bottom at one end of the case, means for actuating said bottom for permitting the end compartment member to drop, means adapted to be controlled by contents in the end compartment for rendering said last means inoperative, and means for carrying the member so dropped to the other end of the case.
3. In a record keeping device, a case with an inclined bottom, a series of compartment members therein having inclined bottom parts, so that the compartment members stand upright on the case bottom, a movable bottom at one end of the case, means for actuating said bottom for permitting the end compartment member to drop, a conveyor for carrying the member so dropped to the other end of the case, and means for preventing the next succeeding compartment member from dropping when said bottom is so actuated.
4. In a device of the class described, an inclined casing, having a bottom terminating short of the lower end of the casing, a series of compartment members in said casing having front walls and side walls, the side walls being beveled at their lower edges, a slidable bottom member at the lower end of said casing, normally yieldingly held in closure position and means for actuating said slidable bottom member for dropping out the lowermost compartment member of said series.
5. In a device of the class described, an inclined casing, having a bottom terminating short of the lower end of the casing, a series of compartment members in said casing having front walls and side walls, the side walls being beveled at their lower edges, a slidable bottom member at the lower end of said casing, means for actuating said slidable bottom member for dropping out the lowermost compartment member of said series, and means for engaging and holding the next upper member of the series while the lowermost member is being released.
6. In a record keeping device, an inclined case having a bottom terminating short of the lower end of the case, a series of compartment members received in said case, a
7. In a record keeping device, an inclined case having a bottom terminating short of the lower end of the case, a series of compartment members received in said case, a slidable bottom at the lower end of said case, a trigger plate pivoted thereto and adapted to normally stand in one position and to be held in another position by the contents of the lowermost compartment member, and means for actuating said bottom member for permitting the lowermost compartment member to drop from the case.
8. In a record keeping device, an inclined case having a bottom terminating short of the lower end of the case, a series of compartment members received in said case, a slidable bottom at the lower end of said case, a trigger plate pivoted thereto and adapted to normally stand in one position and to be held in another position by the contents of the lowermost compartment member, said slidable bottom member having an opening to permit a portion of said trigger plate to project into said case, and means for actuating said bottom member for permitting the lowermost compartment member to drop from the case.
9. In a record keeping device, an inclined case having a bottom terminating short of the lower end of the case, a series of compartment members received in said case, a slidable bottom at the lower end of said case, a trigger plate pivoted thereto and adapted to normally stand in one position and to be held in another position by the contents of the lowermost compartment member, said slidable bottom member having an opening to permit a portion of said trigger plate to project into said case, means for actuating said bottom member for permitting the lowermost compartment member to drop from the case, and means for retaining the next to the lowermost compartment member of the series in the case while the lowermost member is being dropped.
10. In a record keeping device, an inclined casing, a series of members arranged therein, means for successively dropping one member of the series from the lower end of the casing, and means for moving the member so

dropped to the upper end of the series, said means comprising a pair of chains, fingers thereon, and means for actuating said chains.

11. In a record keeping device, an inclined casing, a series of members arranged therein, means for successively dropping one member of the series from the lower end of the casing, and means for moving the member so dropped to the upper end of the series, said casing having a wall at its upper end and having a spring supported by said wall for engaging a compartment member which has been slid upwardly adjacent to said wall within the casing.
12. In a record keeping device, an inclined casing, a series of members arranged therein, means for successively dropping one member of the series from the lower end of the casing, and means for moving the member so

dropped to the upper end of the series, said means comprising a pair of chains and curved fingers thereon, means for actuating said chains, a wall at the upper end of said casing terminating just below the upper end of the casing and adjacent to the upper portions of the chains and provided with slots for said fingers and for said chains.

13. In a record keeping device, a case, a series of compartment members therein, a movable bottom at one end of the case, means for actuating said bottom for permitting the end compartment member to drop, means adapted to be controlled by contents in the end compartment for rendering said last means inoperative.

Des Moines, Iowa, November 12, 1925.

GLEN D. COOPER.
